UNITED STATES PATENT OFFICE.

HENRY P. SCHOENKY, OF ST. LOUIS, MISSOURI, ASSIGNEE TO AMERICAN SHOE MACHINERY & TOOL COMPANY, OF ST. LOUIS, MISSOURI, A CORPORATION OF MISSOURI.

PUNCHING, FEEDING, AND CHANNELING MECHANISM FOR SEWING-MACHINES.

1,242,607.

Specification of Letters Patent.

Patented Oct. 9, 1917.

Application filed October 23, 1916. Serial No. 127,045.

To all whom it may concern:

Be it known that I, HENRY P. SCHOENKY, a citizen of the United States, and a resident of the city of St. Louis and State of 5 Missouri, have invented a new and useful Improvement in Punching, Feeding, and Channeling Mechanism for Sewing-Machines, of which the following is a specification.

10 This invention relates to shoe sewing machines of the lock-stitch type, and is a divisional part of the invention shown and described in my original application for United States Patent for wax thread sewing machines, Serial No. 71,179, filed January 10, 1916.

15 The objects of the invention are simplicity of construction, strength and durability, together with ease of operation and adjustment for all classes of work, such as to make a practical stitching machine for use by ordinary shoe workers without the attention of skilled operators or machinists. Further objects of the invention appear hereinafter.

20 The invention consists in the arrangement of an awl-holder and a channel cutter in a vertically and horizontally movable slide for punching, feeding and channeling the work. The invention further consists in the 25 arrangement of the parts for convenient operation of the machine, and for easy inspection and adjustment or repair, as hereinafter described. What the invention consists in is further set forth in the appended 30 claims.

35 The accompanying drawings show a portion of a shoe sewing machine embodying the invention, only the work table, awl and channel holder, and parts co-operating therewith for punching, feeding and channeling the work being shown, reference being had to my earlier application, referred to above, for drawings and description of the complete machine. The reference numerals used 40 in the accompanying drawings are the same as those used in the drawings accompanying said earlier application, and designate the same parts in all the views. Referring to the drawings,

45 Figure 1 is a front elevation of the lower portion of a machine embodying my invention;

50 Fig. 2 is a horizontal cross-section of the

same on the line 2—2 in Fig. 1, looking down;

55 Fig. 3 is a side view of the right hand side of the portion of the machine shown in Fig. 1;

Fig. 4 is a vertical section of the same on the line 4—4 in Fig. 1, looking in the direction of the arrows;

60 Fig. 5 is a vertical section of the same on the line 5—5 in Fig. 4, looking in the direction of the arrows; and

65 Figs. 6, 7, 8 and 9 are detail views of the adjustable holder for the awl and channel cutter.

70 The machine has a main frame consisting of a base 10, side walls 11 and a front wall 12. Projecting forward from the front wall 70 is a table 13 for supporting the work being sewed. The work table has a slot 19 through it parallel to its front edge for the awl and needle to work through. The work is held by the operator with its top side up, and is 75 guided by hand. The work is fed forward for each stitch by the awl 20, which operates from below the work table in front of the shuttle. The awl is carried by a vertically and sidewise movable holder 21, which also 80 carries a channel cutter 22 for grooving the underside of the work to form a channel for the thread. The work is held in place on the table by a presser foot 32 which operates from above the table. The presser foot 32 85 and needle 41 are mounted above the table in suitable supports not shown in the drawings. The table has a recess below it for the shuttle 52 and bobbin holder 53 which are operated in any suitable manner.

90 The awl, channel cutter, and feeding mechanism are operated from a rotating cam disk 80 mounted on the shaft 81, which is journaled in bearings 82 in the side walls, and which is rotated by any suitable means. 95 The needle and awl are both shown straight, but the invention is not restricted to a straight needle and straight awl. The awl 20 and channel cutter 22 are adjustably secured to the awl holder 21 by means of a 100 clamping bolt 201 which has a pair of vertical holes through it under its head. The channel cutter is shorter than the awl and has a chisel edge. The clamping bolt goes through a transverse hole 202 through the 105 upper end of the awl holder from back to

front, and has a square shoulder 204 on the inner side of its head which engages in a horizontal groove 205 on the back side of the holder. The hole 203 is slot shape, with its long axis vertical, and an eccentric 206 is arranged on the clamping bolt partly in the slotted hole, the diameter of the eccentric portion just filling the width of the hole. The eccentric has a flange which bears 10 against the front of the awl holder around the hole. By rotating the eccentric, the clamping bolt is adjusted horizontally toward one side or the other of the machine, carrying the awl and channel cutter with it. 15 The awl, channel cutter, clamping bolt and eccentric are secured in adjusted position by screwing up the nut 207 on the front end of the clamping bolt.

The awl holder has a horizontal shoulder 211 on its back side below the hole or slot 203 for the lower ends of the awl and channel cutter to rest on. The upward movement of the awl holder carries the awl through the work. The chisel edge of the 25 channel cutter cuts into the under side of the work at the top of the upward movement of the awl holder, thereby forming a shallow groove between the awl holes on the under side of the work.

30 The awl holder 21 is mounted to slide horizontally from side to side in a slide box 23, which in turn is slidably arranged for movement up and down in ways 231 on a forwardly projecting portion of the front wall 12 of the machine frame below and to the side of the work table 13. The ways are provided with gib 234 which can be adjusted to take up wear in the slide box and ways by means of screws 235. The slide box has a horizontal slot in its front side for the awl holder to slide in, and this slot is covered by a removable front plate. The slot has a gib 232 which may be adjusted by screws 233 to take up wear in the slide 21 and walls of the slot.

35 The awl holder 21 extends through the slide box 23 and has a vertical groove 210 on the inner side of its projecting end. This grooved end of the awl holder slides in front of the end of an oscillating shaft 24, and when the awl is in alinement with the needle the center of the groove 210 intersects the axis of the oscillating shaft. This oscillating shaft 24 has a sector 240 on its front end 40 with a groove 241 in its front face intersecting the axis of the shaft. This groove 241 stands vertically in one extreme position of oscillation of the shaft 24, and it makes an angle of about forty-five degrees with the vertical in its other extreme position. An adjusting arm 25 is pivoted eccentrically to the front of the sector 240, and may be clamped in angularly adjusted position on said sector by the thumb nut 250 and J-65 clamp bolt 251 which engages under the

outer edge of the sector. The adjusting arm has a slot through it extending crosswise in front of the groove 241 on the sector, and a stud 252 is mounted in the slot in the adjusting arm with its inner end projecting 70 into the sector groove and fitted to slide therein toward or away from the axis of the oscillating shaft 24 when the adjusting arm is angularly adjusted on the sector. The stud has a shoulder against which the inner 75 face of the adjusting arm bears to clamp the stud in the groove. The outer end of the stud 252 has a roller 254 secured on it which engages in the groove 210 in the awl holder. The sector 240 has a scale marked on its 80 outer edge for setting the adjusting arm 25 to position the stud in the groove 241 at the proper distance from the axis of the oscillating shaft 24 for sliding the awl holder whatever distance is desired for the length 85 of the stitch.

The oscillating shaft 24 is movable axially in its bearings toward the back of the machine to withdraw the sector, stud and roller from the groove 210 in the awl holder. 90 A spring 242 normally holds the shaft and parts carried thereby in forward position. By pushing the sector 240 back, the awl holder may be freed from the roller 254 and shifted sidewise far enough to carry the awl 95 end away from in front of the shuttle, in order that the bobbin may be conveniently removed and replaced. The oscillating shaft has a crank 243 on its back end to which one end of a connecting rod 26 is pivoted. The other end of the connecting rod is pivoted to the lower end of an oscillating lever 27 which is pivotally mounted at its middle on a bearing on the back of the front wall of the frame. The pivotal axis of the lever 27 is parallel to that of the oscillating shaft 24. The upper end of the lever 27 carries a cam roll 270 which engages in a cam groove 28 on the periphery of the cam disk to cause the lever 27 and shaft 24 to oscillate 100 back and forth at the proper time to feed the work, as hereinafter described.

105 The slide box 23 is moved up and down by means of a bell crank lever 29 to which it is connected by a link 30. The bell crank lever is pivotally mounted in bearings at the bottom of the machine frame parallel to the cam shaft and at one side of the cam 80. The rear end of the bell crank lever 29 carries a roller 291 which co-operates with a cam 110 groove 31 in the face of the cam 80 to swing the bell crank lever and raise and lower the slide box for the awl holder, and to hold it motionless in either position. The shape of the cam groove 31 is such that the awl is 115 raised to penetrate the work, is held up until the feeding device has moved the awl into vertical alinement with the needle, and is withdrawn in advance of the downward movement of the needle. That is, first the 120

awl moves up through the work, moves sidewise toward the left to feed the work under the needle, and then withdraws down through the work and moves back toward 5 the right to its initial position out of the way of the needle.

The invention is not restricted to the details of construction shown and described, as it is evident that they are susceptible of 10 modification.

I claim the following as my invention:

1. A sewing machine having a work table, an awl for feeding the work operating in proximity to said table, a sidewise and vertically movable holder for the awl, means for moving said awl holder vertically to cause the awl to penetrate the work, and means for moving said awl holder sidewise in one direction while the awl is in the 20 work and in the opposite direction while the awl is out of the work, said means for sidewise movement comprising a stud adjustably mounted in a radial slot in an oscillating arm and having its end engaging 25 a cross slot in said awl holder, and means for withdrawing said stud from said cross slot to permit said awl holder to be withdrawn sidewise from near said table.

2. A sewing machine having a work table, 30 an awl for feeding the work operating in proximity to said table, a sidewise and vertically movable holder for the awl, means for moving said awl holder vertically to cause the awl to penetrate the work, and 35 means for moving said awl holder sidewise in one direction while the awl is in the work and in the opposite direction while the awl is out of the work, said means for sidewise movement comprising a stud adjustably 40 mounted in a radial slot in an oscillating arm and having its end engaging a cross slot in said awl holder, means for adjusting said stud and securing it in adjusted position in said radial slot to adjust the 45 length of the sidewise movement of said awl holder, and means for moving said oscillating arm away from said awl holder to withdraw said stud from said cross slot to permit said awl holder to be withdrawn 50 sidewise from near said table.

3. A sewing machine having an awl, a vertically and laterally movable holder for said awl, means for adjusting said awl laterally in said holder comprising an eccen-

tric arranged in said holder, a clamping 55 bolt for said awl carried in said eccentric, and means for securing said clamping bolt and awl from angular displacement in said holder.

4. A sewing machine having an awl, a 60 vertically and laterally movable holder for said awl, means for adjusting said awl laterally in said holder comprising an eccentric arranged in a vertical slot in said holder, a clamping bolt for said awl carried in said 65 eccentric, said clamping bolt having a square shoulder engaging in a horizontal groove in said holder for preventing relative angular movement, and means for securing said clamping bolt and awl in said holder. 70

5. A sewing machine having an awl and a vertically and sidewise movable awl holder, a channel cutter carried by said awl holder and movable with said awl for cutting a 75 channel in the work, and means for adjusting said awl and channel cutter sidewise in said holder.

6. A sewing machine having an awl and channel cutter, a vertically movable holder having a support for the ends of the awl 80 and channel cutter formed on its face, means for adjusting said awl and channel cutter laterally in said holder comprising an eccentric mounted in a vertical slot in said holder, a clamping bolt for said awl and 85 channel cutter carried in said eccentric having spaced vertical holes adapted to receive the awl and channel, and clamping means for clamping the awl, channel cutter, and eccentric in adjusted position. 90

7. A sewing machine having a work table and a bobbin holder arranged in proximity thereto, an awl arranged for vertical movement in front of said bobbin holder, said awl being mounted in a holder arranged for 95 vertical and sidewise movement, whereby it can be withdrawn from in front of said bobbin holder to give access thereto, said awl holder having a vertical track on one side, and means slidably engaging said track 100 for positioning said holder, said means being removable to permit said holder to be shifted sidewise to withdraw it from in front of said bobbin holder.

Signed at St. Louis, Missouri, this six- 105
teenth day of October, 1916.

HENRY P. SCHOENKY.
